Inventor: Samuel R. Sargent
By Attorney George H. Christy

UNITED STATES PATENT OFFICE.

SAMUEL R. SARGENT, OF TERRE HAUTE, INDIANA.

SEWING-MACHINE.

SPECIFICATION forming part of Letters Patent No. 284,071, dated August 28, 1883.

Application filed January 8, 1883. (No model.)

To all whom it may concern:

Be it known that I, SAMUEL R. SARGENT, of Terre Haute, county of Vigo, State of Indiana, have invented or discovered a new and useful

5 Improvement in Sewing-Machines; and I do hereby declare the following to be a full, clear, concise, and exact description thereof, reference being had to the accompanying drawings, making a part of this specification, in which—

10 like letters indicating like parts—

Figure 1 is a view in sectional elevation of a portion of the frame and driving mechanism of a sewing-machine illustrative of my invention. Fig. 2 is a view in transverse sectional 15 elevation, the plane of section being in the line x x , Fig. 1, and looking toward the left of that figure; and Figs. 3 and 4 are full size vertical central sections of the respective upper and lower eccentrics and connecting parts.

20 My present invention relates to certain improvements in the connections employed between the main driving-shaft and counter-shaft of sewing-machines and other similar machinery; and it consists in certain combinations of such shafts with eccentrics, eccentric-straps, and pivoted connecting rod or shaft 25 with compensating mechanism, as hereinafter more fully described and claimed.

In the drawings, A represents a portion of 30 the metal supporting-frame of a sewing-machine, in the upper part of which is mounted a horizontal driving-shaft, B, to which rotary motion may be communicated in any suitable way, as by a band over pulley B'. This shaft 35 is employed to operate the needle and take-up mechanism, which is not shown, but may be of any suitable or well-known construction with reference to performing the desired class of work. Rotary motion is also communicated 40 from this driving-shaft to a counter-shaft, C, mounted parallel with it, but beneath the table, which counter-shaft may be journaled in hang- 45 ers D, or other suitable bearings, and is designed to operate the shuttle and feed mech- anism, which may be of any desired construc- 50 tion adapted to perform the desired work. This shuttle and feed mechanism is not shown, as such devices are well known in the art.

In order to secure good working in machines 55 of this class, it is desirable that the two shafts B and C should be so connected as to move or

rotate together without lost motion, and with such direct and positive connection as to insure uniformity of movement. In order to secure these results by easily-constructed but 55 efficient means, I employ two similarly-shaped eccentrics, E and I, formed on sleeve-hubs e and i, which hubs are provided with central bores adapted to fit the shafts B C, respectively. These hubs are bound upon their shafts by set- 60 screws e' i', or equivalent means, in proper positions to bring the eccentrics into a common vertical plane. The upper eccentric is surrounded by a strap, h, which is formed on the upper divided end of eccentric rod or shaft H. 65 The strap is pressed upon the periphery of the eccentric by tension-screw h', which is passed through the rod above the base of dividing-slot h''. The strap is held upon the eccentric as against lateral displacement by a rim or 70 collar, e'', on the side of the hub projection e, and by a removable face-plate, e'', held upon the opposite side by screw e''. The rod H is pivoted at its center by a pin, n, which ex- 75 tends from the rod into a vertical groove, n', (see Fig. 2,) formed in the face of box or block N, the latter being secured to the inner wall of frame-post A by screws n''. The length of groove n' is in excess of the full vertical move- 80 ment of the pin, so that the latter is retained therein through the whole range of motion of the eccentric-rod and thereby forms a pivot-ful- 85 erum for the rod, upon which it turns with lever action under the horizontal movement of its upper end, imparted by the rotation of the eccentric E, thereby giving the two opposite ends of the eccentric-rods vibratory move- 90 ment in opposite directions.

The periphery of the lower eccentric, I, is surrounded by a strap or open ring, a, the 90 ends of which are connected by tension-screw a', whereby the strap may be adjusted to fit the eccentric more or less closely, as desired. This strap is held against lateral displacement by substantially the same means as on the up- 95 per eccentric—that is, by a rim or collar, i'', on the side of the hub-extension, and by a re- 100 movable face-plate, i'', on the other side, which is held in place by screw i''. Connection is made between the strap a and eccentric-rod H by two curved arms, h³ h³, diverging from the lower end of the rod, and by screws e, passed

through slots c' in the arms and into the strap a on its opposite sides. These slots c' permit a small range of vertical movement between the eccentric-strap and the rod sufficient to 5 compensate for difference in vertical reach of the eccentric-rod between its vertical and inclined positions; and in order that this compensating movement may not injuriously affect the uniformity of rotation of shaft C, a pin, r , 10 is extended upward from the eccentric-strap into a socket, r' , formed longitudinally in the body of the rod, the depth of such socket being sufficient to receive a considerable length of pin with sufficient free space for the pin to move vertically therein under the compensating action referred to. This pin-and-socket connection will, in operation, supplement that made by screws and slots c c' in imparting to shaft C uniform movement, and these features 15 of construction, by which such results are secured, I consider an important part of the present invention. Without such compensation for the varying vertical reach of the eccentric-rod, direct connection between the two eccen- 20 trics could not be employed to drive the two shafts in opposite directions without at least considerable lost motion in some of the parts, which would impair the desired uniformity and steadiness of movement, and also increase 25 the noise and wear. Such direct connection is desirable both for mechanical and commercial reasons. By its construction is simplified and cheapened and greater durability is secured.

30 While I have designed my present invention more especially for use in sewing-machines, as above described, yet the same features of connection and compensation may be employed to advantage in other kinds of machinery 35 where it is desired to drive two shafts or ro-

tary bodies in opposite directions by direct connection between eccentrics, and such application I consider as coming within my invention.

I claim herein as my invention—

1. The eccentric-rod H, having slotted divergent arms h^3 and a pin-socket, r' , in combination with eccentric-strap a , having pin r , adapted to enter socket r' , screws c , eccentric I, and shaft C, substantially as set forth. 45

2. In combination with shafts B C, and eccentrics E and I, and eccentric-rod H, straps h and a , pivot-pin n , guide N, and a yielding or compensating connection between strap a and rod H, substantially as described, whereby provision is made for the varying reach of the rod in direction from shaft to shaft. 50

3. The combination of shafts B C, eccentrics E I, eccentric-rod H, having a longitudinally-sliding pivot-bearing between its ends 60 and slotted divergent arms h^3 at one end, eccentric-strap a ; and screws c , substantially as set forth.

4. The combination of eccentrics E and I, pivoted eccentric-rod H, having divergent 65 arms h^3 and a pin-socket, r' , an eccentric-strap surrounding eccentric I, with pin r thereon, adapted to enter and move endwise within socket r' , and connection between the arms h^3 and such eccentric-strap, with freedom of motion between the strap and arms in the direction between eccentrics, substantially as set forth. 70

In testimony whereof I have hereunto set my hand.

SAMUEL R. SARGENT.
